UNITED STATES PATENT OFFICE

94,741

DESIGN FOR A MATCH BOX DOLL

Mae Purcell Flynn, Minneapolis, Minn.

Application May 28, 1934, Serial No. 51,938

Term of patent 3½ years

To all whom it may concern:

Be it known that I, Mae Purcell Flynn, a citizen of the United States, residing at Minneapolis, in the county of Hennepin and State of Minnesota, have invented a new, original, and ornamental Design for a Match Box Doll, of which the following is a specification, reference being had to the accompanying drawing, forming part thereof, wherein:—

Fig. 1 is a perspective view illustrating a match box doll embodying my new design; and

Fig. 2 is a view in side elevation of the same.

The shading applied to the drawing is not intended to designate any particular colors but is merely applied to show contrasting colors.

What I claim is:—

The ornamental design for a match box doll, substantially as shown and described.

MAE PURCELL FLYNN.
